(57) **CLAIM**

We claim the ornamental design for a light shielding cover of a biochemical analyzer, as shown and described.

DESCRIPTION

FIG. 1 is a front, top and right side perspective view of a light shielding cover of a biochemical analyzer showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof; and,

FIG. 8 is an illustrative reference front, top and right side perspective view thereof, showing a using condition.

The broken lines shown in FIG. 8 are included for the purpose of illustrating portions of the light shielding cover of a biochemical analyzer and form no part of the claimed design.
